FIRING KEY

Filed Oct. 16, 1928.

UNITED STATES PATENT OFFICE

JOSEPH B. FEDER, OF EAST ORANGE, NEW JERSEY, ASSIGNOR, BY MESNE ASSIGNMENTS, TO CHAS. CORY CORPORATION, A CORPORATION OF NEW YORK

FIRING KEY

Application filed October 16, 1928. Serial No. 312,786.

This invention is an improvement in firing keys, and more particularly to keys of the quick break type.

One of the primary objects of the present invention is the provision of rotatable mechanism for operating the movable contacts, wherein a spring is utilized to move them in one direction, and plunger operated mechanism to move them in another direction.

Another object is the provision of means for converting the reciprocatory movement of the plunger into rotating movement in a direction to tension the spring, which by its contraction, moves the movable contacts angularly into engagement with the fixed contacts.

A further object is the provision of a simple relatively inexpensive construction, especially adapted for use on shipboard, where in the working parts are fully protected against the elements.

With these and other objects in view the invention consists in the construction and novel combination of parts fully described hereinafter, illustrated in the accompanying drawing, and pointed out in the claims appended hereto, it being understood that various changes in the form, proportion, size and minor details of construction within the scope of the claims, may be resorted to without departing from the spirit of the invention.

In the drawing forming a part hereof:—

Fig. 1 is a longitudinal section of an embodiment of the invention.

Figs. 2, 3, 4, 5 and 6 are sections on the lines 2—2, 3—3, 4—4, 5—5 and 6—6 of Fig. 1.

Fig. 6a is an enlarged detail in section showing the connection of the buttons 21 to the brackets 18.

Figs. 7, 8 and 9 are reduced plan views, showing different mountings for the improved key.

In the present embodiment of the invention, the improved key includes a cylindrical casing 1, usually of brass, and internally threaded at each end. A terminal tube 2, also of brass, is inserted in one end of the casing, and the end 3 of the cable is removably held in the terminal tube. The tube, as shown, has

an internal annular shoulder 4, and surrounding the end of the cable within which is arranged the leads 5 and 5a of the electric circuit, is a gasket 6, held between the shoulder 4 and a ring 7 at the inner end of a collar 8 which is threaded into the terminal tube.

With this arrangement the cable is held firmly in place in the terminal tube, while at the same time it is easily removed, when desired, for any purpose. The leads 5 and 5a pass to connection with lugs 10, on terminal plates 12 and 13, which are mounted on a terminal block 14 held in an insulating tube 15 in the casing. It will be noticed referring to Fig. 1, that the block is secured to the tube 15 by means of screws 16, and each of the terminal plates is connected by screw 17 with fixed contact mechanism mounted on the opposite face of the block. The said mechanism includes an angle bar 18 for each contact plate, the screw 17 firmly connecting the angle bar with the terminal plate.

Each of the angle bars has one of its portions resting on the block 14, and the other extending parallel with the axis of the casing. A pigtail 19 of copper braid is held on this portion of each angle bar by clips 20, and the opposite face of each of the said portion of the angle bar is provided with contact buttons 21.

The contact buttons 21 are composed of a tungsten facing brazed to a base of suitable material. A stud 22 is rigid with each button, and each stud has a loose or rocking connection with the bracket 18 and a conducting connection with the adjacent pigtail, thus to provide electrical connection between the contact button and the pigtail. The rocking action referred to may be by means of a slight clearance of the reduced portion 22a of the stud 22 in its hole in bracket 18 as shown in the enlarged detail, Fig. 6a or by any other suitable means. The fixed contacts are at opposite sides of a shaft 23, journaled at the axis of the tube 15, in a hub 24 on the block 14, and in a cup shaped block 25 held transversely of the casing at the end of the tube 15.

The fixed contacts are adapted to be connected, to close the circuit, by means of contact buttons 26 on wings 27 extending in op-

posite directions from the shaft 23. The contact buttons 26 are similar to the buttons 21, including a tungsten facing secured to a suitable base, and the bases or wings 27 are electrically connected, so that when the buttons 26 are in contact with the buttons 21, the circuit is closed through the conductors 5 and 5a.

The shaft 23 extends through the block 25, which is of insulating material, and is provided with a head 28 within the depression of the cup, the said depression facing away from the contacts. The head 28 has a cam shaped extension 29 for a purpose to be presently described, and the extension has a pin 30, extending axial to the shaft 23, but eccentric thereto because of the head and the extension.

A second shaft 31 is journaled in a bearing 32 in an inner tube 33 in the casing, the said inner tube extending from the end of the tube 15 to the gland 34 of brass, which closes the end of the casing remote from the terminal tube 2. At the end of the shaft 31 adjacent the shaft 23, a head 35 is provided, and the head has a radial extension 36. Upon the extension is a pin 37 parallel with the pin 30, and the pins are connected by a spring 38.

Stop pins 40 and 41 are provided on the bearing 32 for engagement by the extension 36 of the head 35, and the pin 41 is also adapted for engagement by the extension 29 of the head 28. The pins are arranged substantially 180° apart, and they limit the angular movement of the shaft 31 to 180° less the width of the extension 36. The movement of the shaft 23 is limited in one direction by the engagement of the contact buttons 26 with the buttons 21, and in the opposite direction by the engagement of the extension 29 with the pin 41.

It will be apparent from the description that when the shaft 31 is oscillated by mechanism to be presently described, in a direction to move the extension from engagement with the pin 41 to engagement with the pin 40, the pin 37 will be moved to and beyond a position where it is in a diametrical line with the pin 30, thus putting the spring 38 under tension.

As the pin 37 passes the point where it is 180° from the pin 30, the resiliency of the spring operating on the pin 30, will cause a very rapid angular movement of the shaft 23 in a direction to engage the contact buttons 26 with the buttons 21. Springs 39 encircle the studs 22 before mentioned, and act normally to hold the contact buttons 21 radial to the shaft 23, that is, in position to be engaged squarely by the buttons 26, and the rocking connection between the stud 22 and the bracket 18 enables some change in position of the buttons 21 to insure close and accurate engagement.

The block 25 is held in place in the tube 15 by screws 40a similar to the screws 16, and the said block has a flange or extension 41a,

engaging between the adjacent ends of the tubes 15 and 33, as clearly shown in Fig. 1. The shaft 31 is rotated in the present instance from a shaft 41b journaled diametrical of the casing in a filler 42 held in the tube 33, and the abutting at its inner end the bearing 32. This filler is a rack guide for racks to be presently described, and the shaft 41b is provided with two miter gears 43 loosely journaled thereon.

Both gears mesh with a similar gear 44 on the shaft 31. The gears 43 are on opposite sides of the gear 44, and a spur gear or pinion 45 is arranged on and secured to the hub of each miter gear 43, as clearly shown in Fig. 3. A block 46 is mounted to move toward and from the filler 42, and the block carries a pair of racks 47, each of which engages one of the spur gears 45. Referring to Fig. 3, it will be noticed that the racks 47 are arranged on opposite sides of the shaft 41, so that the movement of the racks toward the bearing 32 will act upon the shaft 31 in the same direction.

The block 46 is moved in one direction by means of a plunger 48 provided at its opposite ends with heads 49 and 50. The plunger extends through the gland 34, and a packing 51 held by a nut 52 is provided for the plunger in the gland. The plunger is held from rotating movement with respect to the gland by means of a pin 53 extending radially therefrom, and moving in a slot 54 in the nut, and a spring 55 is arranged between the nut and the packing. The inner head 49 of the plunger engages a similarly shaped depression 56 in the block 46. When the head 50 of the plunger is pressed toward the casing, the block 46 and the racks 47 will rotate the miter gears 43, which in turn will rotate the shaft 31, and cause the movement of the shaft 23 as above set forth.

The block 46 is moved outward by means of springs 58, arranged between the same and the bearing 32. Each spring encircles a pin 59 held by the block 46, and passes through an opening 59a in the filler to engagement with the bearing. It will be noticed referring to Figs. 1 and 5, that the contacts 26 are connected by a fin 60, the fin forming a conducting connection between them.

In Figs. 7, 8 and 9, different forms of mounting for the improved firing key as shown. In Fig. 7, the mounting is of the director type. The firing key similar to that of Fig. 1, and indicated generally at 61, is provided at the end adjacent the plunger 48 with a piston grip 62. An operating lever 63 is pivoted to the grip, and one end of the lever overlies the head of the plunger.

The other end of the lever is in position to be engaged by one of the arms of a U-shaped trigger 64, pivoted to the grip at 65. A guard 66 is provided for the trigger. It is apparent that the key may be held and aimed

like a pistol, and fired by pressing the trigger 64.

In Fig. 8, the mounting is of the hand wheel type. In this arrangement a bracket 67 is secured to the firing key indicated generally at 68 intermediate its ends. A threaded stud 69 extends from the bracket, and the stud is engaged by a nut 70, locked thereto by means of a cotter pin 71. A spacer 72 of brass or the like, is arranged on the stem between the nut and the bracket. In Fig. 9, the mounting is designed for connecting the key to a periscope, the connection being made by a bracket 73 secured to the firing key, indicated generally at 74.

The operation of the key is as follows. With the parts in the position of Fig. 1, when it is desired to close the circuits through the leads 5—5a, the plunger 48 is depressed. The racks 47 rotate the bevel gears 43 in opposite directions, and the gears cooperate to rotate the shaft 31. The spring 38 is put under tension by the movement of the pin 37 from the position of Fig. 4, anticlock-wise to a position directly opposite and in the same diametrical line with the pin 30.

Immediately that the pin 37 passes this point, the spring quickly contracts, swinging the extension 29 toward the stop 40, and bringing the movable contacts into sudden quick and close contact with the contacts 21, thus providing a shortcircuit between the oppositely arranged movable contacts. The movement of the extension 36 continues until it engages the pin 40. When the plunger 48 is released, the springs 58 return it to the position of Fig. 1, and at the same time rotate the shaft 31 in the opposite direction, to return the extension 36 to the Fig. 4 position, and the movable contacts 26 to the Fig. 5 position. That is, the return movement of the plunger 48 again tensions the spring 38, and returns the shaft 23 to the normal position shown in Fig. 5.

What is claimed as new is:

1. In a firing key construction, oppositely arranged fixed contacts, a shaft journaled between the contacts and provided with electrically connected contacts extending radially from the shaft, and positioned to simultaneously engage the fixed contacts when the shaft is rotated in one direction, thereby to close the circuit, resilient means to oscillate the shaft, a reciprocatory plunger, and means interposed between the plunger and the shaft to tension the resilient means during the first part of the movement of the plunger in either direction and to release said means during the last part of its movement, thereby to impart an accelerated motion to the shaft, said means including a shaft in alinement with the first named shaft, and spaced apart therefrom, heads on the adjacent ends of the shafts, the resilient means being connected to the heads eccentrically with re-

spect to the shafts, and means for converting the reciprocatory motion of the plunger into rotary movement of the last named shaft.

2. In a firing key construction, oppositely arranged fixed contacts, a shaft journaled between the contacts and provided with electrically connected contacts extending radially from the shaft, and positioned to simultaneously engage the fixed contacts when the shaft is rotated in one direction, thereby to close the circuit, resilient means to oscillate the shaft, a reciprocatory plunger, and means interposed between the plunger and the shaft to tension the resilient means during the first part of the movement of the plunger in either direction and to release said means during the last part of its movement, thereby to impart an accelerated motion to the shaft, said means including a shaft in alinement with the first named shaft, and spaced apart therefrom, heads on the adjacent ends of the shafts, the resilient means being connected to the heads eccentrically with respect to the shafts, and means for converting the reciprocatory motion of the plunger into rotary movement of the last named shaft, the plunger adapted to be manually moved in one direction, and springs for moving it in the opposite direction.

3. In a firing key construction, oppositely arranged fixed contacts, a shaft journaled between the contacts and provided with oppositely arranged wings carrying electrically connected contacts to simultaneously engage the fixed contacts, thereby to connect the same when the shaft is rotated, a second shaft, means to rotate said second shaft, and a resilient connection between the shafts put under tension by the rotation of the second shaft during the first part of its movement, whereby to impart a snap movement to the first shaft, the means for rotating the second shaft including a plunger movable axially of the shaft, and means interposed between the plunger and the second shaft for rotating said shaft when the plunger is moved axially.

Signed at New York City, in the county of New York and State of New York, this 11th day of October, A. D. 1928.

JOSEPH B. FEDER.
